UNITED STATES PATENT OFFICE.

EMIL KRENZLER, OF BARMEN, GERMANY.

LACE-BRAIDING MACHINE.

1,226,223.

Specification of Letters Patent. Patented May 15, 1917.

Application filed October 10, 1913. Serial No. 794,477.

To all whom it may concern:

Be it known that I, EMIL KRENZLER, residing at Barmen, Milchstrasse 21, Rhenish Prussia, Germany, a subject of the Emperor 5 of Germany, have invented new and useful Improvements in Lace-Braiding Machines, of which the following is a specification:

My invention has reference to braiding or 10 lacing machines on which are produced torchon or single thread laces which are trimmed with laced figures or patterns and it consists in combining with main race circles series of auxiliary circles in such a manner that the carriers may be directly delivered 15 from the main circles to the auxiliary race circles for braiding the figure while in the main race circles or course the ground of the lace is carried out. An important object obtained by my invention is that the new 20 machine is very simple in construction and operation.

The essential features of the invention and of its practical application are fully described in connection with the accompanying 25 drawings.

In the said drawings

Figure 1 shows in a plan view part of the top plate of the machine.

Fig. 2 is a section along line A—A of 30 Fig. 1.

Fig. 3 is a top view showing in skeleton lines the complete arrangement of the race-way.

Similar letters of reference indicate corresponding parts.

The machine consists as usually of the top plate 1, and the bottom plate 2, which are united by means of the pillars 3 that carry the intermeshing drive gears *f*. The heads 40 of the latter are connected in any suitable manner to the main race circles or carrier engaging drivers *a* which are directly located in the bed plate 1 as shown. In connection with these main race circles *a* are arranged according to my invention series of auxiliary race circles *b* in such a manner 45 that each series may form a special braiding course and may be each connected with an adjoining main race circle *a* so that the carriers 50 may be guided directly from a main race circle *a* to its coöperating auxiliary race circle *b* for the purpose of braiding thereon the pattern while at the same time the carriers on the main race circles are shaping or 55 braiding the ground of the lace.

As will be seen from Fig. 3 each group of

main and auxiliary race circles is arranged in a straight line in order that all race circles may be of uniform diameter. For delivering at any time the carriers from the 60 main race circles *a* to the circles *b* and vice versa both coöperating race circles *a*, *b* are provided with four horned drivers 4, 5 as shown while the remaining main race circles *c* are fitted with two horned drivers 6. The 65 drivers 4 and 5 are provided with four horns, since each of the drivers coöperates with at least three adjacent drivers, in catching the carriers and passing the same from one race circle to the other. The drivers 6 which coöperate with two drivers or their 70 adjacent drivers, during the operation of the machine, are provided with only two horns, the same being located on opposite sides thereof to allow the horns of the adjacent drivers to coöperate every half turn of the drivers 6. The movement, arresting and governing of the carriers is effected in a known manner by means of the gears *f* on the shafts or pillars 3; said gears are made 75 to engage the coupling members *g*, *g*¹, the said member *g*¹ being seized by a fork *g*² seated on a vertical shaft *g*³ that is journaled in the plates 1, 2 and upon which bears a spring *k* which separates the members *g*, *g*¹. 80 By drawing the said shaft *g*³ by means of the angle levers *g*⁴ and rods *h*, *i* through the jacquard machine or any other pattern apparatus the members *g*, *g*¹ are connected and the drivers are rotated. The rods *h* 85 are connected in a known manner with the main pattern apparatus which makes periodically half a turn and the rods *i* are connected with an additional pattern apparatus which works in the intervals so that they 90 operate the coupling members *g*, *g*¹ every quarter turn of a driver and according to this mode of working the partly conically shaped ring socket *o* of the drivers 4, 5 is provided with recesses *m* into which fits the 95 end of a rigid piece *n* fastened to the bed plate 1. It will be seen that a locking device of this kind may be operated to lock the carriers after and for each quarter turn 100 of the drivers. Instead of employing two successively working pattern apparatuses, only one may be used.

Between four adjacent main and auxiliary circles is fastened under the bed plate 1 on a pillar *q* a square guide piece *p* and contrary 110 to the known machines having driving circles, the carriers used in my machine are

provided with a pin or projection *r* which sliding along the guide piece *p* holds the said carrier in contact or engagement with the respective driver. In case of braiding special patterns the drivers *b* may be fitted with less than four horns. As stated above the common drivers *c* are provided with two horns and the locking devices for the carriers traveling thereon are operated after 10 every half turn of a driver.

What I claim is:—

A lace braiding machine comprising a chain of main race circles having two-horned drivers, a chain of auxiliary race

circles interposed in the chain of main race circles, said auxiliary race circles having four-horned drivers, a chain of race circles alongside said auxiliary race circles and having four-horned drivers coöperating with the drivers of the auxiliary race circles for moving a carrier, and means for locking the drivers of the auxiliary race circles after each quarter turn thereof. 15 20

EMIL KRENZLER. [L.S.]
